MAGNETIC DISC TRANSDUCING MACHINE

Hari Matsuda, Evanston, Ill., and Robert W. Bornschlegel, Mountain View, Calif., assignors to Ampex Corporation, Redwood City, Calif.

Filed May 4, 1970, Ser. No. 22,790

Term of patent 14 years

Int. Cl. D14—01

U.S. Cl. D26—14

—FIG. 1

FIG. 2

FIG. 1 is a front, top and right side perspective view of a magnetic disc transducing machine showing our new design, and

FIG. 2 is a right side elevation view, to an enlarged scale, of the machine of FIG. 1, the left side being a mirror image of the right side, the back being substantially identical to the front, and the bottom being conventionally plain.

We claim:

The ornamental design for a magnetic disc transducing machine, substantially as shown and described.
